X-RAY TUBE

Rudolf Thaller, Kiel, Germany, assignor to Ernst
Pohl, Kiel, GermanyApplication October 5, 1934, Serial No. 747,103
In Germany April 14, 1934

3 Claims. (Cl. 250—35)

In all the known constructions of X-ray tubes the sharpness of the image at every point of the image carrier (photographic plate, fluorescent screen and the like) depends on the angle of 5 inclination of the focal surface to the ray leading to said point. If, for example, the focal point is band-shaped there is found in the X-ray photograph a noticeable and often very detrimental falling off of sharpness from the middle towards 10 the sides and especially from the part of the image turned towards the anode to the part turned towards the cathode. This property of X-ray tubes of giving images of unequal sharpness is generally referred to as astigmatism. But 15 also elliptical and circular foci produce this effect if the focal surface makes an angle (generally between 45 and 80°) with the image plane. Strictly speaking only a point focus or a spherical focal surface can give an astigmatic image. Circular or annular foci with surface parallel to the 20 image plane would produce practically anastigmatic images but they would have to be very small in view of the total sharpness which decreases with the size of focus. In order not to 25 diminish too much the mean total sharpness of the image linear foci have been used. This construction of tube however is very liable to astigmatism.

The present invention relates to an X-ray tube 30 of high output which will take a much higher load than the ordinary linear focus tube and is not less satisfactory than the tubes with rotating anode for instantaneous exposures, but which operates without astigmatism. In this new tube 35 the surface which emits the X-rays is the outer surface, which is uniformly bombarded with electrons, of a narrow cone made of a metal of high melting point, for example tungsten, having an apex angle of about 30° or less and having 40 its axis at right angles to the image plane in use. With this arrangement the effective image-forming focal surface appears substantially as a circle from every point of the image plane.

The invention is illustrated by way of example 45 in the accompanying drawing.

Fig. 1 shows the X-ray tube with parts broken away.

Fig. 2 explains the action of the conical anode. Fig. 3 shows a detail on a large scale.

Fig. 4 is a section along line 4—4 of Fig. 3 on a smaller scale.

Figs. 5 and 6 show diagrammatically other possibilities of arranging auxiliary electrodes.

Figs. 7 to 9 show modified details.

According to Fig. 1 the conical anode *a* is se-

cured to the anode support *A* which is fixed in the glass bulb *R* of the X-ray tube in such a manner that the cone axis is at right angles to the tube axis. In order that the conical anode *a* may be uniformly bombarded with cathode rays (electrons) several glow cathodes *n* surrounding the anode *a* and preferably consisting of helically wound wire may be used which are arranged in a collecting device *h* provided on the cathode support *K*. 5

In the diagrammatic explanatory Fig. 2, *b* is the edge of the base of the effective part of the anode cone, *c* is the cone axis, the extension of which intersects the image plane *g* in the point *e*. The points in which the separate generating 15 lines of the cone *a* when produced beyond its apex, intersect the image plane *g* form a circle *f* on this plane. From all points lying within the circle *f* the base circle *b* of the anode cone *a* is completely visible. The effective image-forming focal surface is always circular although the effective focal surface is the conical surface seen from above. Since the base circle *b* of the cone is parallel to the image plane, the foreshortening of the diameter *d* as observed from a point on 20 the circle *f* is very small. If, for example, the vertical angle *α* of the cone is 22°, the greatest foreshortening of the diameter *d* of the base of the cone as seen from a point on the circle *f* is 25

$$d \cdot \cos \frac{\alpha}{2} = d \cdot \cos 11^\circ = 0,9816 d$$

the cone as seen from a point on the circle *f* is less than 0.12 mm. with a cone having a base of, for example 6 mm. diameter. Consequently the 35 sharpness of the image is practically uniform within the circle *f*. Furthermore the effective electron emitting anode area corresponding to the conical surface is more than five times the area of the base circle, thus procuring a relatively high radiating intensity as compared with the small apparent area of the focal spot, which ensures a most sharp image. 40

In practice the cone need not have a straight generating line; this may be somewhat curved, 45 as shown in Fig. 7, so that the conical surface is for instance a hyperboloid of revolution.

The cone may be cooled by radiation or by conduction. In the latter case the cone may be embedded in a material of good conductivity, such 50 as copper. If the cone *a* is made hollow it may be cooled by means of a medium circulating rapidly in its interior. This modification is shown in Fig. 8, according to which the anode support *A* is also hollow and a tube *q* for supply- 55

- ing a cooling fluid is arranged within its hollow space p and introduced with its end into the hollow space r of the anode a , so that fluid may circulate as indicated by the arrows.
- 5 The collecting device illustrated consists of a drum-like metal casing h , the axis of which coincides with the axis of the cone. The plain wall i of the casing which faces the base of the cone has an opening k for the conical anode a .
- 10 The other end wall j of the casing has an opening m opposite the apex of the cone a for rays to pass out. The metal casing h is given a potential opposite to that of the anode. The opening k is made so large that with a high vacuum no discharge can take place directly between the anode and the casing.
- 15

In the construction according to Figure 3 the axes of the helical wires n which are in a plane with the axis of the cone a are parallel to the 20 axis of the cone. They may also be inclined to it so as to intersect each other; for example they may be parallel to the opposed generating lines 25 of the conical surface, as shown in Fig. 9. Experiments have shown that when the drum-like 30 collecting device is correctly dimensioned the axes may run parallel to the cone axis without the bombardment of the conical surface becoming non-uniform, whether with a small emission (currents of a few mA) or with a very high emission (currents up to and over 1,000 mA).

The glow wires n are shown in Fig. 3 as being connected with the drum h of the supporting device at their left hand ends. In consequence thereof they are connected in series, if their free 35 right hand ends are connected with the terminals of the source of heating current, and have the same potential as the collecting device. A connection in parallel may be obtained, either without changing anything in Fig. 3, by connecting 40 the free ends of the wires with one and the same terminal of the heating current source and the drum h with the other terminal, or by passing the left hand ends of the wires n with proper insulation through the wall of the drum h and 45 connecting both ends of each wire directly with the terminals of the current source. In this case of course the potential of the glow wire may be different from that of the collecting device.

In order to vary the emission value with consistent heating of the glow wires, especially when using a pulsating tube current, it is possible to provide near to the glow wires auxiliary electrodes, for example in the form of grids or rods (Figure 3), the potential of which is different from that of the glow wires. By means of various arrangements of these auxiliary electrodes (see Figures 4, 5 and 6) and by regulating their potential it is possible to influence the manner in 10 which the bombardment is distributed over the conical surface of the anode and more particularly to obtain a more uniform bombardment of the cone surface.

When using only two diametrically opposite glow wires the drum h is preferably given, as shown in Fig. 4, an oval cross-section with the longer axis in the plane passing through the two glow wires. If more than two glow wires are used the drum is preferably made of circular 20 cross-section.

I claim:

1. Röntgen tube comprising an envelope, an anode having a focal portion in the form of a cone, said cone having an apex angle of not more than 30°, a collecting device in the form of a metal casing surrounding said cone and having a radiation opening axially opposite the apex of the cone, and a plurality of substantially equidistant glow cathode wires arranged within said metal casing and between its shell and said anode cone and extending longitudinally of said cone.

2. Röntgen tube as claimed in claim 1, comprising two glow cathode wires the axes of which lie approximately in a plane with the axis of the anode cone, and a plurality of auxiliary electrodes also arranged within said metal casing between its shell and the anode cone and also extending longitudinally of the cone.

3. Röntgen tube as claimed in claim 1, comprising two glow cathode wires the axes of which lie approximately in a plane with the axis of the cone, said metal casing being of oval cross-section with the longer axis coinciding approximately with the common plane of the cone axis and the glow wire axes.

RUDOLF THALLER.
